(74) Attorney, Agent, or Firm — Santosh K. Chari; CPST Intellectual Property Inc.

(**) Term: **15 Years**

CLAIM

(21) Appl. No.: **29/660,123**

We claim the ornamental design for a combined shelf talker with connecting tabs, as shown and described.

(22) Filed: **Aug. 17, 2018**

DESCRIPTION

(51) **LOC (13) Cl.** **20-03**

FIG. 1 is a front perspective view of the first embodiment for a combined shelf talker with connecting tabs, showing our new design;

(52) **U.S. Cl.**

FIG. 2 is a top view thereof;

USPC **D20/43**

FIG. 3 is a left side view thereof;

(58) **Field of Classification Search**

FIG. 4 is a right side view thereof;

USPC D10/109.1, 109.2, 113.4; D11/165, 166,
D11/181, 182; D20/10, 19, 21, 29, 37,

FIG. 5 is a front perspective view of the first embodiment for a combined shelf talker with connecting tabs, shown in an environment of use;

D20/39, 40, 41, 42, 43, 99

FIG. 6 is a top perspective thereof;

CPC G09F 7/00; G09F 7/12; G09F 7/14; G09F

FIG. 7 is a front perspective view of the second embodiment for a combined shelf talker with connecting tabs, showing our new design;

7/16; G09F 7/18; G09F 2007/122; G09F

2007/1804; G09F 2007/1834; G09F

2007/1886; G09F 9/00; G09F 13/00;

G09F 13/02; G09F 13/04; G09F 13/0018;

G09F 13/22; G09F 2003/1895; G09F

15/00; G09F 15/0037; G09F 15/02; G09F

15/025; G09F 17/00; G09F 2007/0075;

G09F 23/00

FIG. 8 is a top view thereof;

See application file for complete search history.

FIG. 9 is a left side view thereof;
